UNITED STATES PATENT OFFICE.

HOWARD M. BALLOU, OF NORTH ATTLEBORO, MASSACHUSETTS, ASSIGNOR TO R. BLACKINTON & CO., OF NORTH ATTLEBORO, MASSACHUSETTS, A COPARTNERSHIP.

VANITY CASE.

Application filed November 22, 1923. Serial No. 676,446.

To all whom it may concern:

Be it known that I, HOWARD M. BALLOU, a citizen of the United States, and resident of North Attleboro, in the county of Bristol and State of Massachusetts, have invented certain new and useful Improvements in Vanity Cases, of which the following is a specification.

This invention relates to vanity cases and particularly to that type of vanity case which it is desired to use as a container for different kinds of face powder so as to expose either kind of face powder for convenient use at will.

Heretofore it has been proposed to provide such a vanity case with a special insertable holder of a disk form constructed in various ways to afford releasable engagement with the inside of the powder box or container by means of yielding detents, or otherwise, which are adapted to spring into engagement with one or more recesses in the interior wall of the box.

The present invention, however, omits such special holder device and consists, essentially, in the construction of the powder plaques themselves in such a way that a pair of powder plaques may be releasably connected together in a slightly spaced relation to engage an interposed portion of the box or container. The invention, therefore, comprises, generally speaking, a container or box usually provided with covers, in combination with a pair of powder loaded disks provided on their opposed or inner faces with mutually engaging fastening means by which they are releasably held in engagement with an interposed portion of the casing. A further improvement consists in the construction of the powder plaque itself, as an element in the combination, forming a distinct and separate article of sale to be used in suitable containers.

These and other features of the invention will be described in the following specification and will be defined in the claims hereto annexed.

In the accompanying drawings I have illustrated a preferred form embodying the principles of the present invention, in which:

Figure 1 is a plan view of the powder-containing vanity case with the hinged lid thrown back to expose the interior and with

one of the disks which carries the powder exposed to view.

Figure 2 is a vertical central section of the complete vanity case equipped with my improved self-retaining powder plaques.

Figure 3 is a plan view of one of the powder-carrying disks provided with the male fastening member.

Figure 4 is a similar view of the other disk provided with the female fastening member.

In the practice of the invention, according to the form illustrated in the drawings, the container or body portion 1, of the casing is of annular form and is provided, intermediate of its open ends, with an inwardly projecting annular rib or shoulder 2 which forms a ledge against which the two opposed powder laden disks have supporting engagement.

As is usual in this class of devices, the body of the container is provided with covers 3 and 4 suitably connected with the body member 1, as by means of hinges 3^a and 4^a. Flanged rims or lips 3^b and 4^b, serve to frictionally grip the edge portions of the body member so as to keep the lids from accidental opening. According to usual practice, mirrors 5 are set in bezels 6, with which each cover is provided.

The upper powder or rouge plaque, as shown in Figure 2, comprises circular disk 7 whose central portion carries a projecting tongue or ball member 7^a, of a ball and socket coupling and is loaded with powder on its outer face, as shown at 7^b. It will also be noted that the disk 7 is provided with a perforation 7^c, whose function will be presently explained.

The cooperating plaque comprises the disk 8, in which is centrally secured the socket or female member 8^a, of the snap fastener coupling and also is loaded by any desired kind of face powder, as indicated at 8^b, and is also provided with a perforation 8^c.

A pair or couple of cooperating powder plaques, having usual mutual interlocking fastening means, can be inserted in the opposed open ends of the container 1, on opposite sides of the internal ledge or rib 2, and may be releasably secured in that position by merely springing the central portions together to engage the two cooperat-

ing members of the fastening devices together.

When the powder of each plaque becomes worn down to the carrying disk, the disks 5 may be separated very readily by thrusting a pin or wire through the aperture 7^e, or the aperture 8^e, whichever is first uncovered, and the pressure of the inserted pin or wire against the back of the opposite 10 plaque serves to disengage the plaques from one another so that they will readily fall out of the container. The ledge or projection 2, forms a stop interposed between the two members so that, when fastened together by the snap fastener or other form 15 of coupling, neither plaque can drop out of place.

While other forms of interlocking fastener might be used, the ordinary ball and 20 socket snap fastener can be made so cheaply and applied so readily that it forms a convenient separable attaching means for holding the two plaques together inside the casing. It will, of course, be understood that 25 the plaques, while small enough to be admitted inside the casing, are of sufficiently large diameter not to pass through the interior of the rib or ledge 2.

While the apertures for the insertion of 30 the separating wire or pin are shown at some distance from the center, in which position the thrust gains the benefit of a certain leverage in separating the parts, yet it will be understood that a centrally located aperture, to permit direct thrust through one 35 fastening member against the other, is equally within the scope of the invention.

What I claim is:

1. A vanity case embracing in its construction an annular body with open ends, 40 covers for closing the respective ends, the body being provided with an interiorly projecting ledge, and powder-carrying plates provided with means for detachably connecting them together with their edges in engagement with opposite sides of said ledge, substantially as described.

2. A vanity case embracing in combination 50 an annular body member forming a container for powder plaques placed in back to back relation with their powder coated sides facing outwardly, said body member being provided with an inwardly projecting means forming a stop adapted to engage the peripheral portion of each powder plaque, a pair of powder plaques arranged on opposite sides of said stop, and means for releasably connecting said plaques together, substantially as described.

60 3. In a vanity case, the combination of a container provided with an inwardly projecting rib, a pair of powder plaques embracing disks coated with powder on one side and provided on their other side with

mutually cooperative attaching means by 65 which the disks are interconnected and held together with their peripheral portions on opposite sides of said rib, substantially as described.

4. In a vanity case, the combination with 70 a powder-plaque container, of a pair of powder plaques insertable therein from opposite sides of the container and provided with mutually interlocking means forming 75 releasable fastening connection with each other whereby they are retained in engagement with the container to prevent their dropping out of place, substantially as described.

5. In a vanity case, the combination of a 80 container, a pair of powder plaques mounted back to back therein, the back of each plaque being provided with a releasable fastener device arranged to interlock with the co-acting fastener of the other plaque and 85 serving to hold them releasably connected on opposite sides of an interposed portion of the container, substantially as described.

6. A powder plaque embracing in its construction a disk having one face coated with 90 powder, and having a snap fastener element exposed on its back, said fastener element being formed to interlockingly engage a cooperative fastening element by which the disk is held releasably to the container, substantially as described.

7. A powder plaque for use in a vanity case embracing a disk having one face coated with powder and having disposed in the middle portion of its opposite face one member of a snap fastener exposed to be engaged by a cooperative member when inserted in a vanity case, whereby the plaque may be releasably secured in the case, substantially as described.

8. A cooperating pair of powder plaques embracing disks adapted to carry powder on their outer faces and having mutually inter-engaging ball and socket fastening means exposed on their opposed faces when placed back to back, whereby both plaques may be releasably secured together in spaced relation to engage the interior of a suitable vanity case, substantially as described.

9. Means for carrying two kinds of face powder for use in a vanity case embracing a pair of separable disks provided on their inner opposed faces with mutually engaging fastening means, and carrying on their outer faces compacts of face powder, one or both of said disks being perforated to allow insertion of a pin for thrusting one away from the other, in order to disengage the plaques for removal, substantially as described.

In witness whereof, I have subscribed the 125 above specification.

HOWARD M. BALLOU.
